John F. Day, Bloomfield, Conn., and Harold F. Maschin,
Westfield, Mass., assignors to The Westfield Manufacturing Company, Westfield, Mass., a corporation of Massachusetts

Application January 27, 1955, Serial No. 34,260

Term of patent 7 years

(Cl. D90—1)

Fig. 1 is a top plan view of a bicycle tank showing our new design;

Fig. 2 is a side elevational view;

Fig. 3 is a front elevational view thereof; and

Figs. 4, 5, 6, 7, 8 and 9 are cross-sectional views taken on lines 4—4, 5—5, 6—6, 7—7, 8—8, and 9—9, respectively, of Fig. 1.

The fragmentary dotted line disclosure of a bicycle frame is shown only for purposes of illustration.

We claim:

The ornamental design for a bicycle tank, substantially as shown and described.
